(57) **CLAIM**

We claim the ornamental design for a light, as shown and described.

DESCRIPTION

FIG. 1 is a perspective view of a light;

FIG. 2 is a top plan view of the light;

FIG. 3 is a front elevation view of the light;

FIG. 4 is a right side elevation view of the light;

FIG. 5 is a rear elevation view of the light;

FIG. 6 is a left side elevation view of the light; and,

FIG. 7 is a bottom plan view of the light.

The broken lines shown in the drawing views illustrate portions of the light that form no part of the claimed design.
